William A. Taylor, Louisville, Miss.

Application November 16, 1953, Serial No. 27,626

Term of patent 14 years

(Cl. D35—2)

To all whom it may concern:

Be it known that I, William A. Taylor, a citizen of the United States, residing in the city of Louisville, county of Winston, State of Mississippi, have invented a new, original, and ornamental Design for Sealer Attachment for Plows, of which the following is a specification, reference being had to the accompanying drawing, forming part thereof, and in which:

Figure 1 is a top plan view of a sealer attachment for plows showing my new design;

Figure 2 is a side elevational view;

Figure 3 is a rear elevational view; and
Figure 4 is a cross-sectional view taken on the line 4-4 of Figure 2.

I claim:
The ornamental design for sealer attachment for plows, as shown.
